The ornamental design for a portable desalination unit, as shown and described.

DESCRIPTION

FIG. 1 is a front perspective view of a portable desalination unit;

FIG. 2 is a top view thereof;

FIG. 3 is a bottom view thereof;

FIG. 4 is a front view thereof;

FIG. 5 is a back side view thereof;

FIG. 6 is a right view thereof; and,

FIG. 7 is a left view thereof.

The broken lines shown in the drawings illustrate portions of the portable desalination unit and form no part of the claimed design.
